UNITED STATES PATENT OFFICE.

OTIS V. JONES, OF INSULL, KENTUCKY.

CHURN.

Application filed November 8, 1928. Serial No. 318,037.

The invention relates to improvements in churning and has for its principal object the utilization of a certain type of machine used for laundering clothes employing an oscillating shaft that extends into the clothes receptacle and is ordinarily employed to operate an agitator for the clothes to actuate the dashers of a churn structure, said churn structure employing a receptacle mounted within the clothes receptacle of the washing machine, and supported on the supporting means for the agitator, said churn receptacle having a tubular member arranged therein and opening out through the bottom of the receptacle to house the oscillating shaft, and to which the dashers are secured, the clothes receptacle of the washing machine forming an outer casing to receive the churn receptacle and spaced from the walls thereof so that a temperature regulating medium such as hot or cold water may be employed within the space between the casing and the churn receptacle to properly adjust the temperature of the contents of the churn for quick formation of the butter fat from the cream.

The invention will be described in detail hereinafter and will be found illustrated in the accompanying drawings, in which

Figure 1 is a fragmentary view partly in section of a washing machine showing the improved churn mounted therein, the churn structure being shown in vertical section,

Figure 2 is a horizontal sectional view on a plane indicated by the line 2—2 of Figure 1,

Figure 3 is a detail sectional view on a plane indicated by the line 3—3 of Figure 1,

Figure 4 is a side view of the dasher structure showing the closure cap in transverse section, and

Figure 5 is an end view of the dasher structure.

In the drawings similar reference characters are used to designate corresponding parts throughout the several views.

As hereinbefore stated the churn is arranged to be applied to a certain type of washing machine that is shown fragmentarily in Figure 1 and is provided with a clothes receptacle A forming a casing for the churn receptacle 1, having the walls spaced as shown at 2 to receive hot or cold water or ice as may be required to properly adjust the

temperature of the cream for quickly forming the butter fat. The churn receptacle 1 is supported on a flange B that is a part of the clothes receptacle of the washing machine and when used as a washing machine is adapted to support an agitating member (not shown) that is arranged to be driven by the shaft C, that is journaled in a bearing D on the bottom E of the receptacle A and is also journaled in a bearing F secured to a shelf G supported on the legs H. Secured to the shaft C is a pinion I that meshes with a rack bar J having one end engaging a crank K on shaft L that is driven by the motor M by means of the shaft N through the worm gearing O. It will be apparent that the shaft C will be given an oscillatory motion by the gearing consisting of the pinion I engaging the rack bar J driven by the shaft L, that is in turn rotated by the shaft N through the worm gearing O. 3 indicates a tubular member opening out to the bottom 4 of the receptacle 1 as shown at 5 to receive and house the shaft C. The dashers 6 of the churn are secured to depending arm 7 from a cross bar 8, forming a substantially inverted U-shaped structure, and intermediate of the depending arm 7 is a downwardly extending arm 9 having a socket 10 on its lower end shaped to engage the polygonal end c of the shaft C so that operation of the shaft c will actuate the dashers 6, said shaft C giving to said dashers an oscillatory or reciprocating motion. 11 indicates a flanged cap that is slidably mounted on the bar 9 and internally threaded to engage the threaded upper end of the tubular member 3. The lid or cover 12 may be as shown of the removable type or any other type of cover may be substituted.

What is claimed is:—

A churn dasher, consisting of an inverted U-shaped member, dashers on the dependent arms of said member, a bar dependent from said member intermediate of the dependent arms, a socket on said bar polygonal in cross section and adapted to fit a polygonal extension on a drive shaft, and a cap member slidably and rotatively mounted on said bar and adapted to close the upper end of a tubular housing for the shaft.

In testimony whereof I affix my signature.
OTIS V. JONES.
